UNITED STATES PATENT OFFICE.

WILLIAM J. BRADY, OF SAN FRANCISCO, CALIFORNIA.

METHOD OF FORMING CURVED METALLIC PIPES.

SPECIFICATION forming part of Letters Patent No. 337,475, dated March 9, 1886.

Application filed August 11, 1885. Serial No. 174,160. (No model.)

To all whom it may concern:

Be it known that I, WILLIAM J. BRADY, a resident of the city and county of San Francisco, State of California, have invented an Improved Method of Forming Elbows and Curves in Wrought-Iron Pipes and Tubes; and I hereby declare that the following is a full, clear, and exact description of the same, reference being had to the accompanying drawings.

10 My invention relates to a simple and ready method of forming bends, elbows, and curves in wrought-iron piping and tubing formed of riveted joints, by the use of a shaping spline, a parallel made of some suitable elastic wood or hard rubber, without the aid of elaborate drawings and prolonged calculations.

15 The following description fully explains the nature of my said invention and the manner in which I proceed to accomplish and apply the same, the accompanying drawings being referred to by figures and letters.

Figure 1 represents a longitudinal section through a series of angular pipes forming a bend, the first joint showing a band in halves riveted on, and the second joint temporarily secured by an adjustable strap. Fig. 2 is a plan view of a sheet of iron with holes before bending. Fig. 3 represents a section of a band in halves. Fig. 4 represents an elevation of the 20 same. Fig. 5 represents an enlarged elevation view of one of the straps, showing holes and slots for bolts. Fig. 6 is a plan view of the under part of a band. Fig. 7 is a plan view of the upper part of a band. Fig. 8 is a plan 25 view of the under strap. Figs. 9 and 10 are diagrams illustrating the old method of laying out pipe elbows and bends. Fig. 11 is a diagram illustrating the improved method of doing the same. Fig. 12 is a diagram illustrating the 30 improved method of springing a curve with a spline. Fig. 13 is a plan view of one of the bands, or a section, showing the improved method of striking a curve.

In my improved method of forming bends or curves in wrought-iron piping made of riveted joints I propose to save the time and labor required by the old method in accomplishing that purpose. In forming an elbow according to the old method the first step is to 35 strike a semicircle, divide it into a number of

ordinates, and then make tedious calculations in demonstrating, Figs. 9, 10.

My method reduces both the time and work to the minimum, while giving the desired result, and it not only saves time and work in 40 the operation, but so simplifies the work that any ordinary mechanic may perform it.

In applying my method to laying pipe on a course in which angles or curves are required I make a drawing of the diameter of the pipe 45 for which the elbow is required. If it is to be a right-angle elbow, I describe a curved line at the required radius, then divide the outside curve into four, five, or six parts, as may be required, and then draw radii through any 50 two of these adjacent points, Fig. 11, after which I proceed to develop a section or course for the angle, as shown, Fig. 13. I now divide the diameter of the pipe into two equal parts, which will require the division of the circumference into four parts. I then take the line 55 1 on the pipe of the greatest width and place it on the section at A. 3, being the narrowest part of the angle or elbow, is placed on the section at C, and 2, being the center of the 60 angle, is placed on the section in the center of the line of circumference B, and also at the ends B B, allowing for the necessary lap. I am now ready to use the spline h—a parallel 65 of about three-quarters of an inch by three-quarters square by ten feet long, ($\frac{3}{4}'' \times \frac{3}{4}'' \times 10'$)—with which I spring a curve through the points 70 which gives the required curve for the elbow, Fig. 12.

The adjustable strap e is an important feature in my method of forming angles and curves in laying a course of piping made of riveted joints.

The manner of applying the strap is as follows: As soon as a curve is determined, a band, 90 b, conforming to the curve in its lower part, c, and upper part, d, is put over the end of one joint of pipe, and the end of the next joint is let into the band, and both ends are then riveted. Where the course run conforms 95 to the topography of the country and passes up and down hill, bends may be required on the side as well as up or down. By means of the adjustable strap, however, the pipe-laying may proceed without interruption, as the 100

joints of pipe are joined temporarily by the straps. An under strap, e^x , is bolted to the ends or sides of the pipes, as required, while the adjustable strap e , having slots f in one end, is bolted to the upper part of the joints of pipe after they have been adjusted to the curve, Fig. 1. As soon as the required curve or curves have been determined, for the course may require a side as well as an upward curve 5 at a given point, bands composed of an upper and under section, Figs. 6, 7, are placed on the pipes and riveted. The curve required is determined, without any regard to elaborate drawings and calculations, by simply measuring 10 the distance of the openings between the pipes at four points—namely, the widest and the narrowest, and the distance between the pipes at the middle. I then proceed, in the same manner as described for the construction 15 of an elbow, to develop a section of pipe in two pieces, as shown, Fig. 13.

When the section is completed, the straps which have been employed to adjust and hold the pipes to the curve may be removed, and 20

the joint covered and secured permanently by 25 two parts of the band which are riveted to the pipes.

Having thus fully described my invention, what I claim, and desire to secure by Letters Patent, is—

An improved method of forming curves, bends, and angles in wrought-iron pipes and tubes, by drawing a few lines, Fig. 11, developing a section therefrom, as described, Fig. 13, and springing the required curve in the 30 manner described, Fig. 12, and temporarily securing the curved ends of the pipes by straps e , by which the pipes are adjusted and held to the curve until they are permanently secured by bands e^x and riveted, substantially 35 as described; and for the purpose set forth.

In testimony whereof I have hereunto set my hand and seal.

WILLIAM J. BRADY. [L. s.]
